UNITED STATES PATENT OFFICE.

JESSE BEMIS, OF BELTON, MONTANA.

SAW-SET.

1,293,308.

Specification of Letters Patent.

Patented Feb. 4, 1919.

Application filed December 29, 1917. Serial No. 209,521.

To all whom it may concern:

Be it known that I, JESSE BEMIS, a citizen of the United States, residing at Belton, in the county of Flathead and State of Montana, have invented new and useful Improvements in Saw-Sets, of which the following is a specification.

This invention comprehends the provision of a saw set which can be quickly and conveniently manipulated for the purpose intended, and embodies among other features a trip hammer with means for holding the latter in predetermined positions, to regulate the drop thereof consistent with the force required under certain conditions.

Another object of the invention resides in the provision of a manually controlled lever operable in one direction to elevate the hammer, and adapted to be lowered against the saw in its active position, means being employed for automatically holding the handle in any degree of elevation independently of the hammer to permit the saw to be properly positioned therebeneath as the occasion may require.

The invention further contemplates the provision of a device of the above mentioned character wherein the lever is provided with one or more openings for the reception of swaging elements of different characters for use in connection with different type saws, and wherein the swaging elements are disposed in the path of movement of the hammer.

The nature and advantages of the invention will be better understood from the following description when read in connection with the accompanying drawings, the invention residing in the construction, combination and arrangement of parts as claimed.

In the drawings forming part of this specification like numerals of reference indicate similar parts in the several views and wherein:

Figure 1 is a side elevation showing the hammer in lowered or active position.

Fig. 2 is a similar view partly in section showing the hammer in elevated position.

Fig. 3 is a top plan view.

Fig. 4 is a transverse section taken on line 4-4 of Fig. 1.

Fig. 5 is a transverse section taken on line 5-5 of Fig. 1.

Fig. 6 is a front end elevation.

Fig. 7 is a detail view of the lever.

Fig. 8 is a similar view of the pivot for the locking dog.

Fig. 9 shows several forms of swaging elements.

Fig. 10 is a plan view of the anvil showing indicating marks thereon.

Before entering into a detail description of what is herein shown and described I desire to have it understood that the same is merely illustrative of one embodiment of the invention to which I do not limit myself and that such changes in the construction and arrangement of parts may be resorted to when desired as fall within the scope of what is claimed. It might further be stated that the component parts of the invention may be constructed from any suitable material and design.

As shown in this particular instance however the device comprises a base 10 having suitable openings 11 adjacent the opposite ends thereof for the reception of suitable fastening elements for the purpose of securing the base to a suitable support. Rising from the base adjacent one end is a pair of spaced block-like members 12, and projecting forwardly from each block is a bar 13 disposed in spaced parallel relation to the base 10, and terminating an appreciable distance short of the forward end of the base. The space between the base 10 and the bars 13 is adapted to receive the body of the saw in a manner whereby the teeth can be singly disposed upon the anvil 14 carried by the base immediately adjacent the forward end thereof in advance of the bars 13. The anvil may be provided with suitable indicating marks 14' thereon to act as guides for the teeth of the saw so as to secure an even setting for different saws, as shown in Fig. 10.

Connecting the block-like members 12 is a bolt 15 constituting a pivot for the lever 16, the purpose of which will be hereinafter more fully described. The lever is bifurcated at the end which is pivotally associated with the bolt 15, and positioned between the separated portions 17 defined by the bifurcation is one end of the trip hammer, which is provided with a suitable opening for the reception of the bolt 15 upon which it is pivotally mounted independently of the lever 16. The hammer is disposed immediately above the lever 16 and as a unit is approximately half the length of the latter, including a shank 17' and a relatively large head 18. The

hammer is spring operated, a pair of flat springs 19 being preferably employed, having their corresponding ends 20 secured to the upper surface of the block-like members 12, while the opposite extremities of the springs bear upon the cross pin 21 carried by the head 18 of the hammer, and are curved downwardly as at 22 to prevent separation of these parts. The cross pin 21 is 10 grooved adjacent its opposite extremities, thereby defining shoulders 23 between which the free ends of the springs 19 are arranged and thus held against lateral movement as will be readily understood. The springs normally 15 maintain the head 18 of the hammer in contacting engagement with the lever 16, which latter must be elevated to raise the hammer to its elevated or inactive position.

Rising from the forward extremities of 20 the bars 13, and secured thereto in any suitable manner are spaced standards 24 between which both the lever 16 and trip hammer operates. The standards are provided with a longitudinal series of alined openings 25 for the reception of a pivot pin 25, and upon which is pivotally mounted a locking dog 26 for engagement with the head 18 of the hammer to hold the latter in elevated position. The pivot pin 25 may be secured 30 between the standards in any suitable manner, and is preferably provided with a squared portion 27 which is received within the squared openings in one of the standards so as to prevent turning of the pivot, 35 while the locking dog 26 has secured thereto a spring 28 having one of its ends passed through a slot 29 in the pivot pin 25, the spring operating to hold the locking dog in proper position so that its lowermost end 40 will be disposed in the path of movement of the head 18 of the trip hammer. The lower end of the locking dog is provided with a lip 30 adapted to engage within a groove 31 formed in the head 18 of the trip 45 hammer to hold the latter in elevated position. The adjacent edge of the head 18 of the trip hammer is curved as at 32 to cooperate with the beveled portion 33 of the locking dog to prevent binding between these 50 parts, thereby permitting the head 18 of the hammer to rock the locking dog 26 upon its pivot as the hammer is elevated, which places the spring 28 under tension, so that the spring functionates at the proper time 55 to reverse the rocking movement of the locking dog to bring the lip 30 into effective engagement with the groove 31 and thereby hold the hammer in its elevated or inactive position. As hereinabove stated the lever 60 16 is pivotally mounted upon the bolt 15 for movement independently of the trip hammer, and that subsequent to elevating the lever for the purpose of moving the trip hammer to its inactive or elevated position, 65 the lever is then lowered into engagement

with the saw, which latter is positioned upon the base to be dressed. It might here be stated that the lever 16 at a point in its length carries a set screw 34 which can be properly adjusted to engage the body of the 70 saw when the lever is lowered, to hold the saw immovably positioned upon the base. The lever is further provided with transverse openings 35 and 36 respectively to interchangeably receive any one of the swaging 75 elements A disclosed in Fig. 9, whose uses are desired in connection with different type saws. These elements are interchangeably received by the opening 35, while the opening 36 is adapted to receive a relatively 80 broad swaging element A' which is used only when it is desired to take the set out of the saw teeth for the purpose of sharpening the same. However when the swaging elements are associated with the lever 16, 85 and the latter lowered upon the saw, the swaging element engages the tooth of the saw immediately above the anvil 14, and is disposed in the path of movement of the head 18 of the hammer, so that when the 90 latter is tripped it is effectively brought into engagement with the adjacent end of the swaging element, under the influence of the springs 19, thereby driving the element in the direction of the anvil to set the particular tooth of the saw being worked upon. 95

Any suitable means may be employed for tripping the hammer, or in other words moving the locking dog 26 out of engagement with the head 18 thereof, but I preferably employ a flexible element 37 having one end secured to the upper end of the locking dog 26 and its opposite end secured to a trigger 38 pivotally mounted within a slot 39 in the lever an appropriate distance 100 in advance of the trip hammer. The flexible element is passed through an opening in the head 18 of the hammer, and also trained through a suitable guide 40 rising from said head. It is of course to be understood that when the lever 16 is raised to elevate the hammer, the flexible element is slackened to permit the locking dog to be rocked upon its pivot in the manner hereinabove described during its association 115 with the head of the hammer, but when the lever is subsequently lowered to its active position against the saw, the flexible element is drawn taut, so that upon movement of the trigger in a downward direction, the 120 locking dog 26 is moved out of engagement with the head 18 of the hammer through the instrumentality of the flexible element 37, thereby permitting the hammer to be forcibly actuated under tension of the 125 springs 19. Under certain conditions it is necessary to vary the force with which the hammer is lowered, and to provide for this, it is only necessary to position the pivot pin 25 in any of the alined openings in the 130

standards 24, that is to say that the locking dog can be adjusted toward or away from the base 10 to hold the hammer in any degree of elevation, consistent with the

- 5 force of the drop required under the circumstances. Manifestly with the adjustment of the locking dog 26 means must be provided to regulate the length of the flexible element 37, and in this instance I preferably secure the upper end of said element to a pin 41 journaled between spaced apertured lugs rising from the upper end of the locking dog 26, so that upon rotation of the pin in either one or the other direction, the flexible element is wound upon or unwound therefrom, thereby regulating the length of the element so that the hammer can be easily and quickly tripped from any of its elevated positions. The pin is provided with a ratchet wheel 42 with which a spring pressed pawl 43 co-operates to prevent retrograde movement of the pin. Subsequent to the locking of the hammer in elevated position, it is necessary to elevate the lever 16 to properly arrange or position the saw upon the base for the next operation of the hammer, and with a view of automatically holding the lever in elevated position, I preferably provide the forward edge 30 of one of the standards 24 with spaced grooves 44 to receive a spring operated roller 45 associated with the lever and effectively held in engagement with the forward edge of said standards under the influence of the spring 46. The roller is journaled in a frame 47 that is slidably mounted within a longitudinally disposed groove 48 at one side of the lever and held in position therein by means of a guide 49 and the adjacent standard 24. The spring 46 has one end connected with the lever and its opposite end connected with the frame 47 and holds the roller in engagement with the forward edge of the said standard 24. 45 The standards are preferably curved as shown, and in addition to the roller holding the lever in elevated position, independently of the hammer, by being positioned within one of the grooves 44, the roller allows the combined weights of the lever 16 and trip hammer to be easily and quickly elevated. The frame 47 is provided with a finger engaging portion 50 which projects beyond one side of the lever, to permit the frame and roller to be retracted to a position to clear the forward ends of the bar 13, while the lever is being singly lowered to active position upon the base 10. In this position of parts the roller 45 under the influence of the spring 46 is held in effective engagement with the forward end of the adjacent bar 13, thereby assisting the set screw 34 in holding the saw immovably positioned upon the base 10. The device is 60 not only easy to manipulate, but the com-

ponent parts are compactly arranged to produce both a simple and effective machine for the purpose intended.

What is claimed is:—

1. A device of the class described comprising a base, an anvil carried thereby, a trip hammer pivoted on said base, a lever pivoted to said base and disposed beneath the hammer, and a swaging tool carried by the lever and disposed in the path of movement of said hammer. 70
2. A device of the class described comprising a base, an anvil carried thereby, a trip hammer pivoted on said base, a lever pivoted thereon beneath the hammer, means for holding said hammer in elevated position, means having connection with the lever for tripping said hammer, and a swaging tool carried by the lever and disposed in the path of movement of the hammer. 75
3. A device of the class described comprising a base, an anvil carried thereby, a trip hammer pivoted on the base, a lever pivoted thereon and disposed beneath the hammer, springs normally holding the hammer in contact with said lever whereby the latter is used to elevate said hammer, means for holding the hammer elevated independently of said lever, means having connection with said lever for tripping the hammer, and a swaging tool carried by the lever and disposed in the path of movement of said hammer. 80
4. A device of the class described comprising a base, an anvil carried thereby, a pivot pin thereon, a trip hammer pivoted on the pin, a lever pivoted on the pin and disposed beneath the hammer, a swaging element carried by the lever and disposed in the path of movement of said hammer, said lever being adapted to elevate the hammer, means for holding the hammer in elevated position, means for holding the lever in any degree of elevation independently of said hammer, and means having connection with said lever for tripping the hammer. 85
5. A device of the class described comprising a base, an anvil carried thereby, spaced standards rising from the base, a spring operated dog pivoted between said standards, a trip hammer pivoted on the base, a lever pivoted thereon and disposed beneath the hammer, and adapted to elevate said hammer, said dog being disposed in the path of movement of the hammer and adapted to engage the latter to hold the hammer in its elevated position, a swaging tool carried by the lever and disposed in the path of movement of said hammer, and means having connection with the lever for effecting a release of said hammer. 90
6. A device of the class described comprising a base, an anvil carried thereby, spaced standards rising from said base, a trip hammer pivoted on the base, a lever 100
7. A device of the class described comprising a base, an anvil carried thereby, a pivot pin thereon, a trip hammer pivoted on the pin, a lever pivoted on the pin and disposed beneath the hammer, a swaging element carried by the lever and disposed in the path of movement of said hammer, said lever being adapted to elevate the hammer, means for holding the hammer in elevated position, means for holding the lever in any degree of elevation independently of said hammer, and means having connection with said lever for tripping the hammer. 105
8. A device of the class described comprising a base, an anvil carried thereby, spaced standards rising from the base, a spring operated dog pivoted between said standards, a trip hammer pivoted on the base, a lever pivoted thereon and disposed beneath the hammer, and adapted to elevate said hammer, said dog being disposed in the path of movement of the hammer and adapted to engage the latter to hold the hammer in its elevated position, a swaging tool carried by the lever and disposed in the path of movement of said hammer, and means having connection with the lever for effecting a release of said hammer. 110
9. A device of the class described comprising a base, an anvil carried thereby, spaced standards rising from said base, a trip hammer pivoted on the base, a lever 115
10. A device of the class described comprising a base, an anvil carried thereby, spaced standards rising from the base, a spring operated dog pivoted between said standards, a trip hammer pivoted on the base, a lever pivoted thereon and disposed beneath the hammer, and adapted to elevate said hammer, said dog being disposed in the path of movement of the hammer and adapted to engage the latter to hold the hammer in its elevated position, a swaging tool carried by the lever and disposed in the path of movement of said hammer, and means having connection with the lever for effecting a release of said hammer. 120
11. A device of the class described comprising a base, an anvil carried thereby, spaced standards rising from said base, a trip hammer pivoted on the base, a lever 125
12. A device of the class described comprising a base, an anvil carried thereby, spaced standards rising from said base, a trip hammer pivoted on the base, a lever 130

4
 pivoted thereon and disposed beneath the hammer, and adapted to move the hammer to elevated position, a locking dog pivoted between said standards for engagement with the hammer to hold the latter in elevated position, said dog being adjustable toward and away from the base to regulate the drop of the hammer, a swaging tool carried by the lever and disposed in the path of movement of said hammer, and means having a connection with said lever for effecting a release of said hammer.

7. A device of the class described comprising a base, an anvil carried thereby, a trip hammer pivoted upon the base, a lever pivoted thereon and disposed beneath the hammer, spaced standards rising from the base at the opposite sides of said lever, a locking dog pivoted between the standards for engagement with the hammer to hold the latter in elevated position, a trigger element pivoted on the lever, a flexible element connecting the trigger with said dog to effect a release of the latter upon movement of said trigger, and a swaging tool associated with the lever and disposed in the path of movement of said hammer.

8. A device of the class described comprising a base, an anvil carried thereby, spaced standards rising from the base, a trip hammer pivoted on the base, a lever pivoted thereon and disposed beneath the hammer and movable with said hammer between said

standards, a locking dog pivoted between said standards in the path of movement of said hammer and adapted to engage the latter to hold the hammer in elevated position, said dog being adjustable toward and away from the base to regulate the drop of the hammer, a trigger carried by the lever, a flexible element connecting the trigger with said dog to effect a release of the latter upon movement of the trigger, means for regulating the means of said flexible element consistent with the adjustment of the dog, and a swaging tool carried by the lever and disposed in the path of movement of said hammer.

9. A device of the class described comprising a base, an anvil carried thereby, a trip hammer pivoted on the base, a lever pivoted thereon and disposed beneath the hammer and adapted to move the latter to elevated position, means for holding said hammer elevated, means for releasing said hammer, a cross pin projecting beyond the opposite sides of the hammer, springs having one end secured to the base and their opposite ends engaging said cross pin to forcibly actuate the hammer upon release of the latter, and a swaging tool carried by the lever and disposed in the path of movement of said hammer.

In testimony whereof I affix my signature.

JESSE BEMIS.
